LEATHER CARRYING CASE

Frank Mashek, Chicago, Ill.

Application August 12, 1937, Serial No. 158,631

3 Claims. (Cl. 150—1.6)

The invention relates to leather brief or carrying cases.

One object of the invention is to provide an improved construction for this type of case in which the edges or margins are united together for durability so they will withstand severe wear and will also present an attractive and well-finished appearance.

Other objects of the invention will appear from the detailed description.

The invention consists in the several novel features of construction hereinafter set forth and more particularly defined by claims at the conclusion hereof.

In the drawing: Fig. 1 is a perspective of one form of brief-case embodying the invention, a corner of the outer cover of leather being folded away from its backing for illustrative purposes. Fig. 2 is a sectional perspective of the marginal portion of one side of the brief-case shown in Fig. 1, on an enlarged scale. Fig. 3 is a perspective of a brief-case provided with a plurality of expandible pockets and embodying the invention. Fig. 4 is a section on line 4—4 of Fig. 3. Fig. 5 is a section on line 5—5 of Fig. 3.

In Figs 1 and 2, the invention is applied to a brief-case which comprises sides 7 connected together by a fold to form the back 8 and a strip 9 of flexible material, such as stout thin woven cloth, along the inner and top edges of the sides 7, which permit expansion of the sides and are adapted to be secured together by hookless fasteners 10 for closing and opening the case. In this type of case, the sides 7, when the case is open, are adapted to lie flat on a table or desk.

In building up the case, a sheet 11 of somewhat flexible backing or stiffening material such, for example, as cardboard or strawboard, and a sheet 12 of material for forming an inner lining or fastening, are cut into shape to conform to the sides 7 and back 8 of the case. Sheet 12 may be of thin leather or fine cloth which is adapted to serve as a finish for the inside of the case and to protect the contents from contact with the stiffening sheet 11. The strip 9 is then laid with its outer edge so it conforms to the margin of the stiffener sheet 11 and liner sheet 12. A binding strip 13 preferably of leather and of sufficient width to extend around the edges of sheets 11, 12 and strip 9 and to lap the outer faces of sheet 11 and the inner face of strip 9, is extended as at 13^a around the edges of said sheets and strip and folded to lap and fit against the entire margin of the outer face of strip 9, as

at 13^b and to lap and fit against the margin of the outer face of the stiffening sheet 11, as at 13^c.

While the binding strip 13 is thus folded around the edges and margins of sheets 11, 12 and strip 9, all are sewed together on a sewing machine by a seam 14 which passes through the binding strip adjacent its inner edges and the sheets 11 and 12 and strip 9. This operation will secure the backing sheet, the facing or liner sheet, and the binding strip 9 together. A sheet 15 of leather is cut to conform to the shape of the case desired to form the outer cover for the sides 7 and back 8. The edge of this sheet is finished by suitable tools so that it will be smooth and possess a finished appearance. The inner structure comprising strip 9, sheets 12 and 11 which have been bound together by the seam 14 and binding strip 13 are placed on the leather cover sheet 15 which is then sewed to the inner structure by a seam 16 which extends through the cover sheet 15, sheets 11 and 12, strip 9 and both of the sides 13^b and 13^c of the binding strip 13. The seam 16 is made outwardly from the seam 14 so that the outside of seam 14 will be covered by the leather sheet 15 and only the seam 16 will be visible when the case is closed.

The finished edge 15^a of sheet 15 terminates substantially in or near the plane of the outer portion 13^a of the binding strip 13. The finished edge 15^a of the leather cover sheet 15, the binding strip 13, and the seam 16 are visible from the outside of the case and impart an attractive finished appearance to its edge construction in connection with the leather cover sheet.

This construction provides a margin which is stout and durable because the inner seam binds the binding strip, the backing and liner strips and the expandible strip together, and the outer seam secures together the same parts and the leather cover sheet.

The margin of the brief-case presents an attractive and finished appearance on account of leaving visible the cut edge of the leather on the outer cover, the single seam on the outer face of the cover, and the folded edge of the binding.

In Figs. 3 and 4, the brief case comprises a front side 18, a back side 19, with a construction 21 forming a flap to extend over and close the top of the case, and pockets in the case and between the sides which are formed by partitions 23 which are connected to one another and to the sides by an expandible or bellows member 24 of leather, which extends along the ends and bottom of the case.

The front side 18 comprises an outer or cover-

sheet of leather 26 and an inner facing or liner 27 of thin material, such as fine fabric or leather. The back-side 19 and the flap 21 comprise a cover-sheet 26' of leather and a liner 27' of fine fabric or leather. Bellows-member 24 is looped around the edges of partitions 23 and sewed thereto as at 23^c. The outermost strip 24^a of member 24 is extended to lap the margins of the inner faces of the liner sheets 27, respectively. Binding strips 28 are folded around the edge of one portion of each strip 24^a and the edge of the abutting liner 27 and to lap, as at 28^a, 29^b, the outer faces of liners 27 and strips 24^a, respectively. These strips 28, liners 27, and strips 24^a, respectively, are stitched together by a seam 32 which extends through the liner and strip 24^a and both portions 28^a of the binding strip adjacent the inner edge of the latter.

The leather cover-sheet 26 is cut to fit the side 18 and the cover-sheet 26' is cut to fit side 19 with its flap 21. The edges of the leather sheets 26, 26' are finished off and correspond substantially to the outer edge of the binding strips. The outer cover-sheets of leather are each secured to the previously formed structure composed of the liner strips 27, the member 24 and the binding strips 28 by seams 30, which are stitched through the lapped margins of the cover sheets, the binding sheets, and strips 24^a, respectively. This edge-construction is strong and durable because the liner-sheet, expandable member, and binding-strip are united together by the inner seam and are also united together and to the outer cover by the outer seam. The finished edge is attractive in appearance, the single outer seam, finished edge of the leather, and the edge of the binding strip being visible, while the inner seam is invisible from the outer sides of the case.

The invention is not to be understood as restricted to the details set forth, since these may be modified within the scope of the appended claims, without departing from the spirit and scope of the invention.

Having thus described the invention, what I claim as new and desire to secure by Letters Patent is:

1. A carrying case comprising sides connected together at one margin and a flexible connection between the sides, the sides comprising an outer covering sheet of leather and an inner liner of relatively thin flexible material, the connection

comprising a strip having its margin lapping the margin of the inner face of the liner, and a binding strip folded around the edges and lapping the marginal portions of the outer faces of the connecting strip and the liner, the lapping portions of the binding strip and the liner and connecting strip being stitched together by a seam spaced from the edge of the liner, the outer covering of leather having a finished edge conforming to the binding strip and secured by a seam extending through the covering, the binding strip, the liner and the connecting strip outwardly of the first mentioned seam. 5

2. A carrying case comprising sides joined together by a connecting back at one margin, a connecting strip between the sides, the sides comprising an outer sheet of leather, an inner lining of thin flexible material and a stiffening sheet between the liner and the covering sheet, the connecting strip having its margin lapping the margin of the liner sheet, a binding strip folded around the edges and the sides of the backing and liner sheets and the connecting strip, the binding strip, the liner and the connecting strip being stitched together by a seam spaced from their edges and passing through them, the outer leather sheet having its edge conforming to the binding strip and stitched thereto by a seam extending through both folds of the binding strip, the liner and backing sheets and the connecting strip outwardly of the first-mentioned seam. 20 25

3. A carrying case comprising sides joined together by a connecting back at one margin, a connecting strip between the sides and means for detachably securing the margins of the strip together to close the case, the sides comprising an outer sheet of leather, an inner lining of thin flexible material and a stiffening sheet between the liner and the covering sheet, the connecting strip having its margin lapping the margin of the liner sheet, a binding strip folded around the edges and sides of the backing and liner sheets and the connecting strip, the binding strip, the liner and the connecting strip being stitched together by a seam spaced from the edge and passing through them, the outer leather sheet having its edge conforming to the binding strip and stitched thereto by a seam extending through both folds of the binding strip, the liner and backing sheets and the connecting strip outwardly of the first-mentioned seam. 30 35 40 45 50
